INFLATABLE SOUND PRODUCING ANIMAL
TOYIrving Kwasnik, Passaic, N. J., and Leopold
Endzweig, New York, N. Y.

Application August 2, 1950, Serial No. 177,164

3 Claims. (Cl. 46—88)

1

This invention relates to new and useful improvements in hollow toys adapted to be inflated and having sound producing means, and, more particularly, the aim is to provide a novel and valuable such toy, as one of the doll or animal type, wherein the sound producing means is actuated by the movement of an air stream therethrough with said air stream one which wholly interiorly of the toy passes from one portion thereof to another during the sound making. By a toy of the doll type is meant one which generally reproduces or suggests the human corpus; and by a toy of the animal type is meant one which generally reproduces or suggests the corpus of an animal other than a human one, as the body of a dog, an elephant, a lion, a bear, or the like.

The object of the invention, more specifically, is to provide, in a toy of the kind above described, a relatively inexpensive yet highly practicable arrangement such that the toy when inflated is an exceedingly faithful reproduction of the corpus which it is supposed to represent, with this reproduction a full three dimensional one all over the corpus of the toy.

This object is in part attained by constructing the toy so that the same incorporates an outer non-stretchable skin but not necessarily an air-tight one, and an inner air-tight skin stretchable under inflation, and by so constituting said inner skin that when it is air inflated its own stretchability coacts with the non-stretchable distensibility of the outer skin to round out tautly all portions of the latter as predetermined; with such predetermination, in the case, for instance, of an animal, patterned on the actual contours of the body and body adjuncts, that is, the corpus, of the animal. Such body adjuncts, as that expression is used herein, would include the four legs and the head of a four-legged animal, or the two legs and the two arms and the head of a two-legged animal.

Said object is in further part attained by constructing said inner skin of two or more sheet material pieces, one piece, for example, providing a main bag for forming the body and four of the aforesaid body adjuncts of the toy when said main bag is inflated, and the other piece an auxiliary bag for forming the fifth of said body adjuncts when said auxiliary bag is inflated.

Said object is in further part attained by connecting directly and in an air-tight manner a fitted edge adjacent small opening left in the first-named bag with a fitted edge adjacent small opening left in the second-named bag; and, in-

2

cidental to thus connecting said openings, securing the sound producing means in place inside the inner skin and in extension through both said openings so that one end portion of said means projects into one bag and the opposite end portion of said means projects into the other bag.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a detached perspective view of the said auxiliary bag.

Fig. 2 is a detached perspective view of the said main bag.

Fig. 3 is a sectional view on line 3—3 of Fig. 2.

Fig. 4 is a detail perspective view of the sound productive device.

Fig. 5 is a frontal elevation of the inflatable inner portion of the toy in collapsed condition.

Fig. 6 is a view similar to Fig. 5 but illustrates the device in inflated condition.

Fig. 7 is a frontal view of the completely assembled toy in expanded condition.

Fig. 8 is a sectional view on line 8—8 of Fig. 7.

Fig. 9 is a sectional view on line 9—9 of Fig. 7.

Fig. 10 is a perspective view on a large scale of a modified form of sound producing means.

Fig. 11 is a large scale, fragmentary view similar to a portion of Fig. 8 but illustrating the modified means.

Referring now to the drawings more in detail, the toy shown, but merely illustratively and solely by way of example, is reproductive of the animal toy generally called a Teddy bear; and, accordingly, the above-mentioned main and auxiliary bags have outlines to conform with the features of such a toy. As here shown the inflatable portion of the toy is made up of a main bag 15 and one auxiliary bag 16, although it will be understood that in other instances more than one auxiliary bag would be utilized. The main bag 15 comprises a one-piece molded formation of rubber, plastic or other stretchable or expandable material, see Fig. 2. As shown in Fig. 3, said bag is formed with arm and leg portions and also with a narrow open end neck portion 17.

The auxiliary bag 16, which is formed in the same manner as the main bag, is adapted to form the head of the toy and is outlined accordingly.

Said auxiliary bag is also provided with a narrow open end neck portion 18. At this point it is to be mentioned that whereas the bags 15 and 16 preferably are formed each in one piece, they can, if desired, be formed each of two or more sheets of stretchable material having their perimetal edges suitably secured together.

Referring again to Fig. 2, one of the leg portions of main bag 15 is provided at its end with a small extension or nozzle 20 by which air can be forced into the toy as will appear hereinafter.

Since the illustrative embodiment of the invention shown in the drawings and now being described is a toy bear, and the head of such an animal is roughly pear-shaped and tapering toward its neck-remote end, and said head is elongate not only in the direction of said taper but also in a direction substantially perpendicular to the direction of elongation of the torso of the animal, the auxiliary bag 16 pursuant to the invention is provided with the side elevational aspect when deflated as shown in Fig. 1; so that when said bag 16 at its neck portion 18 is secured as shortly to be described to the main bag 15 at its neck portion 17, the flat of said bag 16 is disposed at right angles to the flat of the main bag 15 as shown in Fig. 5, the smaller or snout end of the bag 16 being the near end thereof in Fig. 5.

The sound producing means is as a whole designated 19, see Figs. 4 and 8, the same being shown as a small elongate assemblage of parts of a well-known kind, including a reed 21 and a reed carrier 22. Also, a tubular support 23 for the sound producing means is provided, such support being open at both ends, having the reed carrier 22 suitably fixed in a partition 24 intermediate its ends.

In order to connect together in an air-tight manner the neck portions of the inner skin main bag 15 and of the inner skin auxiliary bag 16, thereby to lock the sound producing means 19 in place between said neck portions and this in a way to constitute the interior of the tubular support 23 as the sole air passageway between the interiors of said two bags, the neck portions 17 and 18 are made each of a considerably shorter circumferential length than that of the tubular support 23. Thus, when the tubular support 23 is inserted well up into the neck portion 18 of auxiliary bag 16, the said neck portion tightly grips the support; and when the neck portion 17 of the main bag 15 is engaged over neck portion 18, an even tighter grip on tubular support 23 is afforded, see Figs. 6, 8 and 9. If desired, an adhesive or elastic band not here shown, may be clamped over the neck portions 17 and 18 even more securely to clamp them on the tubular support 23.

For inflation of the bags 15, 16, by breath exhalation, as by some member of the child's family, the already mentioned air inflation device is provided. This, in the present case shown as placed near the heel portion of the foot of the right leg portion of the main bag 15, is illustrated as comprising a rubber air inlet tube 20 formed integral with bag 15, and a rubber or metal rod 25 easily deliberately to be temporarily removed from the tube 20 to allow blow-up of the bags 15, 16, yet adapted when reinserted tightly into said tube as in Fig. 8 to become frictionally dependably anchored therein in an air-tight manner.

The bags 15, 16, completed and equipped with the sound producing means 19 and the air inflation device 20, 25 as above described, is now

ready, in deflated condition, to be enclosed in an outer skin 26.

The sheet material used for making the outer skin 26 is desirably a textile material having a plush-like outer pile as indicated in Figs. 7 and 8. The said outer skin 26 is so made, from as many specially patterned cut pieces of said material as required, and with these cut pieces interconnected by as many seams as required, in order to include in said outer skin a torso subdivision, a head subdivision, two arm or fore leg subdivisions and two hind leg subdivisions all adapted to exhibit exceptionally natural rotundities when distended as predetermined. These outer skin subdivisions, furthermore, are so individually proportioned and relatively arranged that, after proper insertion in the outer skin of the bags 15, 16 in as yet uninflated condition, and following closing up of the one seam of the outer skin left unclosed pending insertion of the inner skin into the outer skin; full inflation of the inner skin would cause the latter to become disposed as indicated in Figs. 7 and 8; and as a consequence the outer skin would become distended as also shown in said figures, thus to have all the outer skin subdivisions exhibit the intended exceptionally natural rotundities.

As will be understood, the just mentioned proper insertion of the bags 15, 16 into the outer skin 26 would be an insertion of the former into the latter such that the principal or torso portion of the main bag 15 would be in the torso subdivision of the outer skin, the two arm or fore leg portions of said main bag would be in the two arm or fore leg subdivisions of the outer skin, the two hind leg portions of said main bag would be in the two hind leg subdivisions of the outer skin, and the auxiliary bag 16 would be in the head subdivision of the outer skin with the snout end of said bag 16 at the snout end of said head subdivision.

The air inflation device 20, 25 or equivalent could, for instance, and as shown in Fig. 8, be protruded through a small opening left in the outer skin 26; this opening, perhaps, along one of the seams hereinabove mentioned as interconnecting the specially patterned cut pieces of the outer skin.

With the inner skin 15, 16 inside the toy as completed, and with said inner skin fully inflated, so that, despite the fact that a life-like fully three-dimensional replica of a bear is had yet with such an inexpensive air container incorporated as one comprised preferably of two molded bags, the sound producing means 19 will be actuated following a compression of any part of the torso, any part of the head, or any part of any of the arms or legs to an extent to effect even a fairly slight temporary localized deformation of the bear from its life-like fully three-dimensional normally maintained shape.

In a sound producing means such as that herein shown at 19, an air stream forced to pass therethrough in one direction, that is, in a downward direction in Fig. 8, causes the sound production; whereas an air stream forced to pass through said means in the opposite direction is soundless. Thus, if any part of the bear other than its head is compressed, there will be no sound made until such compression is released and until consequently the extra air forced into the bear's head may rush back out of the bear's head to equalize the air pressure all over the interior of the bear. Such rush back of air, in other words, actuates the sound production.

means. If, however, the head of the bear is compressed, the sound producing means will be actuated as an accompaniment of such compression, because during said compression air will be forced downwardly through the sound producing means.

A modification of the above described construction is illustrated in Figs. 10 and 11 where-in like parts are given the same reference numerals as hereinbefore, with a prime added. The modification consists in replacing the sound producing means 19 with the means 19' illustrated in Figs. 10 and 11, which latter means are adapted to assist in binding the neck portions of the bags 15' and 16' thereon and also to provide ready access to the actual sound productive means for purposes of adjusting the latter to obtain a desired sound therefrom.

Referring to Figs. 10 and 11, the means 19' comprises a pair of tubular members 28 and 30, the former being threaded internally as at 31, and the latter having an externally threaded extension 32 of reduced diameter which is adapted to be screwed into the member 28. As shown, the reduced diameter of extension 32 provides an annular shoulder 33 at the base thereof, said shoulder being adapted to abut the end edge of member 28 when said extension is drawn up in the latter. Member 30 is provided with an internal partition 24' in which is mounted the reed carrier 22'.

The construction is such that when the member 28 is inserted completely within the neck portion 18' of auxiliary bag 16' the end of said neck portion is drawn, by its own tension, into engagement with the end edge of the member, and when the member 30 is inserted into the neck portion 17' of main bag 15' the end edge of said neck portion is drawn into engagement with the annular shoulder 33. Thus, when extension 32 is drawn up in member 28 said neck end portions are tightly gripped between the end edge of member 28, and the annular shoulder 33. This serves not only to securely fasten said neck portions on the members 28 and 30 but also to provide a washer-like air tight seal between the members.

It will readily be seen that with the construction just above described, the reed 21' is readily accessible for adjustment purposes.

It is to be emphasized that the invention is not to be limited to the material herein mentioned as preferred or desirable to be used for the inner skin, as any material suitable for the purpose pursuant to the invention may be used; and, similarly, it is to be emphasized that the invention is not to be limited to the material herein mentioned as preferred or desirable to be used for the outer skin, as any material suitable for the purpose pursuant to the invention may be used.

While we have illustrated and described the preferred embodiments of our invention, it is to be understood that we do not limit ourselves to the precise constructions herein disclosed and the right is reserved to all changes and modifications coming within the scope of the invention as defined in the appended claims.

Having thus described our invention, what we claim as new, and desire to secure by United States Letters Patent is:

1. An inflatable toy simulative of an actual living creature of the kind having a body and a plurality of body adjuncts, comprising, in combination, a hollow structure having therein a

plurality of air-tight chambers and a passageway between said chambers which is the sole avenue of air communication therebetween, a sound producing means actuatable by air flowing through said passageway, and, as parts of said hollow structure, an inner air-tight skin stretchable under inflation and an outer substantially non-stretchable skin, said chambers being within said inner skin, but the entire interior of said outer skin being a single chamber, said inner skin having a principal portion which while predeterminedly confined and while the inner skin is fully inflated establishes a three dimensional replica of the body of said creature, said inner skin also having a plurality of lesser portions variously extended from said principal portion and each of which lesser portions while predeterminedly confined and while the inner skin is fully inflated establishes a three dimensional replica of a different one of the body adjuncts of said creature, said inner skin being made of a main larger bag and a smaller auxiliary bag, each of said bags having a narrow neck portion surrounding an opening to the interior of that bag, said sound producing means including a pair of tubular members, one threaded internally and the other having a threaded extension of reduced diameter, said neck portions being stretched over said members with the end edges thereof being drawn by their own tension against the proximate end edges of the members, said extension being drawn up in the other said member with the said end edges of the neck portions being compressed between said members.

2. An inflatable toy simulative of an actual living creature of the kind having a body and a plurality of body adjuncts, comprising, in combination, a hollow structure having therein a plurality of air-tight chambers and a passageway between said chambers which is the sole avenue of air communication therebetween, a sound producing means actuatable by air flowing through said passageway, and, as parts of said hollow structure, an inner air-tight skin stretchable under inflation and an outer substantially non-stretchable skin, said chambers being within said inner skin, but the entire interior of said outer skin being a single chamber, said inner skin having a principal portion which while predeterminedly confined and while the inner skin is fully inflated establishes a three dimensional replica of the body of said creature, said inner skin also having a plurality of lesser portions variously extended from said principal portion and each of which lesser portions while predeterminedly confined and while the inner skin is fully inflated establishes a three dimensional replica of a different one of the body adjuncts of said creature, said outer skin being comprised of a plurality of joined specially patterned pieces of sheet material so respectively shaped, dimensioned and arranged that with said inner skin fully inflated the said predetermined confinements of said principal and lesser portions of the inner skin are all effected by the enclosing outer skin, said inner skin being made of a main larger bag and a smaller auxiliary bag, each of said bags having a narrow neck portion surrounding an opening to the interior of that bag, said sound producing means including a pair of tubular members, one threaded internally and the other having a threaded extension of reduced diameter, said neck portions being stretched over said members with the end edges thereof being drawn by their own tension against the proximate

mate end edges of the members, said extension being drawn up in the other said member with the said end edges of the neck portions being compressed between said members.

3. An inflatable toy simulative of an actual living creature of the type having a body, a head and a plurality of body adjuncts, comprising, in combination, a pair of one-piece bags of stretchable material, one forming said head and the other said body and its adjuncts; a narrow open end neck portion extending from each said bag, a first tubular member threaded internally and which is inserted completely into a said neck portion, the tension of the latter drawing the end edge thereof into contact with the end edge of the tubular member; a second tubular member having an externally threaded extension of reduced diameter; all of said second member save said extension being inserted into the other neck portion so that the end edge of the latter is drawn by its own tension against the end edge

of the wider portion of the member, and a sound productive device mounted within the said second member, said extension being drawn up in the other said member with the said end edges of the neck portions being compressed between said members.
